INTERMITTENT STRIP FEED MECHANISM
OF THE RECIPROCATING TYPE

Albert S. Howell, Culver, Ind., assignor to Bell & Howell Company, Chicago, Ill., a corporation of Illinois

Application December 26, 1947, Serial No. 793,836

23 Claims. (Cl. 88—18.4)

1

My invention relates particularly to intermittent strip feed mechanism for feeding motion picture film strips provided with the usual feed perforations.

Objects of the invention reside in the provision of a novel, desirable and effective intermittent strip feed mechanism, which is particularly adapted for motion picture projecting machines, which is precise in operation, which is so constructed that the reciprocating structure thereof may have a relatively small amount of momentum, which, involving a pivoted lever for reciprocating the toothed feed means of the mechanism, desirably provides rectilinear reciprocation of the feed means connected portion of the lever, which provides for engagement and disengagement of the toothed feed means of the mechanism with the usual feed perforations of a strip being fed in such a manner that wear on the feed tooth or teeth of the feed means and the feed perforations of the strip and noise incident to such engagement and disengagement are materially reduced, which provides a desirable side guide bearing for the pivoted oscillating lever or levers of the mechanism, which provides for counterbalancing the reciprocating structure of the mechanism, which provides, preferably as an operating adjustment, for adjusting the extent of the reciprocating strip feed and return movement of the toothed feed means or shuttle to conform with the spacing of the feed perforations of the strip and so accommodate for shrinkage or expansion of the strip, and which provides, preferably as an operating adjustment, for adjustment of the strip feed and return stroking range of the toothed feed means for "framing."

Certain features of the embodiment of the invention hereinafter described are described and claimed in my co-pending application for Letters Patent of the United States, Serial No. 762,748, filed July 22, 1947, for improvement in Intermittent Strip Feed Mechanism.

The invention will be better understood by reference to the accompanying drawing in which—

Figure 1 is a partial interior view in rear elevation of a motion picture projecting machine embodying my invention;

Figure 2 is a partial sectional view taken substantially on the line 2—2 of Figure 1;

Figure 3 is a partial sectional view taken substantially on the line 3—3 of Figure 1;

Figure 4 is a partial sectional view taken substantially on the line 4—4 of Figure 1;

Figure 5 is a perspective view of one of the parts of the mechanism hereinafter described;

2

Figure 6 is a partial sectional view taken substantially on the line 6—6 of Figure 2;

Figure 7 is a vertically condensed perspective view of the feed shuttle of the mechanism;

Figure 8 is a partial sectional view taken substantially on the line 8—8 of Figure 1 and showing the strip feed guide of the mechanism; and

Figure 9 is an exaggerated diagrammatic view showing the strip feeding action of my invention.

Referring to the drawing and particularly to Figure 1, a frame part 1 is disposed vertically and transversely of the machine, and a horizontal forwardly extending shaft 2 is mounted for rotation on suitable bearings, not shown and which

are carried with the frame part, and the shaft extends through the intermediate portion of a transversely extending recess 3 in the rear face of the frame part. See Figures 1 and 2. A toothed feed shuttle 4 is spaced transversely from the

shaft 2 and is disposed at one end of the recess 3, and is mounted for vertical reciprocatory strip feed and return movement, as hereinafter more

fully described.

Two substantially identical levers 5 and 6 of light truss construction are disposed within the recess 3, and extending horizontally and transversely of the axis of the shaft 2, have a pair of

corresponding ends thereof in the region of the shuttle and the corresponding end of the recess, and have the other shuttle remote ends thereof

disposed in the region of the shuttle remote end of the recess, the shaft 2 being disposed intermediate the ends of the levers. The levers 5 and

6 are coaxially pivotally mounted at the shuttle remote ends thereof for independent vertical movement and extend correspondingly from their pivotal axis in overlying relation, and the pivotal

mounting of the levers comprises as follows:

A vertically extending bearing block 7 is disposed within the recess 3 at the shuttle remote end thereof, and is mounted on the frame part 1

for vertical adjustment by means of headed screw

studs 8 passing through vertical slots 9 through the bearing block and screwthreaded into the frame part 1, the bearing block being conveniently so adjustable by suitable mechanism comprising a shaft 11 pivotally mounted on the frame part and provided with an eccentric portion 12

rotatably and slidably engaged in a horizontal slot 13 in the bearing block. See Figures 1 and 6.

40 A bearing stud 14 extends correspondingly with the movement planes of the levers 5 and 6 and transversely of the reciprocating strip feed and return path of the shuttle 4, see Figures 2 and 6,

45 and is slidably mounted for corresponding

50 movement and extends through the bearing block 7 and is secured to the frame part 1.

45 A bearing stud 14 extends correspondingly with the movement planes of the levers 5 and 6 and transversely of the reciprocating strip feed and return path of the shuttle 4, see Figures 2 and 6,

55 and is slidably mounted for corresponding

55 movement and extends through the bearing block 7 and is secured to the frame part 1.

adjustment in a bore 15 through the vertically intermediate portion of the bearing block 7, this stud being conveniently so adjustable by a suitable mechanism comprising a shaft 16 pivotally mounted on the frame part 1 and provided with an eccentric portion 17 rotatably and slidably engaged in a vertical slot 18 in the stud, it being observed that the stud is vertically adjustable with the bearing block 7 and is adjustable independently of the bearing block corresponding with the movement plane of the levers 5 and 6 and transversely of the reciprocatory path of the shuttle 4.

The major portion 19 of the stud 14 is of elongated rectangular cross section having its greater dimension disposed horizontally and this portion is slidably engaged in a correspondingly shaped portion 21 of the bore 15 to prevent rotation of the stud on its axis. The stud portion 19 includes the end portion 22 of the stud which is directed toward the shuttle 4, and this end portion projects from the bearing block 7 and has its upper and lower surfaces convexly curved linearly of the stud as best shown in Figure 6 to constitute of the portion 22 a bearing member establishing a pivotal axis for the levers 5 and 6.

The pivotally mounted end portion of each of the levers 5 and 6 is provided with a bearing slot 23 extending radially of each lever and transversely of the reciprocatory path of the shuttle 4, and this slot of each lever embraces the bearing member 22 for pivotal and radial movement of each lever on the bearing member 22, the bearing slot of each lever constituting a linear bearing member having bearing engagement with the bearing member 22 longitudinally of the reciprocatory path of the shuttle to correspondingly pivotally confine each lever and to permit relative movement between each lever and the bearing member 22 radially of each lever and transversely of the reciprocatory path of the shuttle.

The vertical face of the bearing block 7 which faces the levers 5 and 6 is provided with two parallel vertically extending bearing grooves 24, the bottom surfaces 25 of which constitute rectilinear bearing members extending in the same vertical plane and longitudinally of the reciprocatory path of the shuttle. The shuttle remote ends of the levers 5 and 6 respectively extend in the grooves 24, and the end surfaces 26 of the shuttle remote ends of the levers constitute linear bearing members having bearing engagement with the bearing members 25 and extend and have linearly of the reciprocatory path of the shuttle a convex substantially arcuate form having its axis at the shuttle adjacent ends of the levers of which the shuttle adjacent end of the lever 5 is connected with the shuttle, as hereinafter described, for reciprocating the shuttle with oscillation of this lever, the bearing members 25 and 26, as shown, being desirably disposed at the shuttle remote ends of the levers and adjacent the bearing members 22 and 23, and the bearing members 22 and 23 are disposed intermediate the lineal extent of the bearing members 25 and 26 so that that these latter bearing members engage on opposite sides of the bearing members 22 and 23 as the levers are oscillated, the bearing members 26 rocking on the bearing members 25 as is evident in Figure 6.

A stud 27 is secured on the frame plate 1 between the bearing member 22 and the shaft 2 and projects into openings 28 through the levers 5 and 6 and is provided with blind bores 29 facing in the direction of the bearing block 7. See 75

particularly Figure 2. Push rods 31 have washers 32 secured at corresponding ends thereof and these heads are respectively slidably engaged in the bores 29 of the stud 27. The other ends of the push rods are pointed and are respectively engaged in grooves 33 at the ends of the lever openings 28 adjacent the shuttle remote ends of the levers 5 and 6. Compression springs 34 are respectively disposed in the bores 29 and, oppositely engaging the bottoms of these bores and the washers 32, urge the push rods 31 and consequently the levers radially of said levers and transversely of the reciprocatory path of the shuttle 4 and toward the bearing block 7 to maintain the bearing members 25 and 26 in engagement.

As the levers 5 and 6 are oscillated, they pivot on the bearing member 22 which establishes the pivotal axis of the levers, and the bearing members 23, which are slidably and pivotally engaged on the bearing member 22, permits the bearing members 25 and 26 to control the radial positioning of the levers, and the bearing members 25 and 26 are so formed that in cooperation with the bearing members 22 and 23, they effect a desirable rectilinear reciprocation of the toothed feed means or shuttle connected portion of the lever 5 and the corresponding portion of the lever 6.

The shuttle remote ends of the levers 5 and 6 are positioned normal to the movement plane thereof in adjacently spaced relation by the sides of the grooves 24, and are similarly positioned at portions thereof remote from their pivotal axis, see Figures 1 and 2, by three parallel longitudinally tensioned wire-like bearing members 35 extending vertically in correspondence with the movement of the levers and respectively disposed on the outsides of and between the levers, so that each lever is disposed between two of these bearing members and has bearing engagement therewith, the bearing members 35 being positioned and longitudinally tensioned by vertically spaced tensioning devices 36 common to these bearing members and mounted on the frame plate 1 and secured with opposite ends of the bearing members 35 and tensioning the same.

Each of the levers 5 and 6 is provided with an intermediate opening 37 through which the shaft 2 extends, and two radial cams 38 and 39 are fixed on the shaft 2 for rotation therewith and are respectively disposed in the openings 37 of the levers and are respectively engaged between vertically spaced parallel opposing slide bearing surfaces 41 of the lever openings 37, which bearing surfaces extend radially of the levers, for oscillating the levers with rotation of the cams and shaft, the cams 38 and 39 corresponding in contour and being timed in diametrically opposite relation so that the levers 5 and 6 are oscillated in timed opposite movement phase relation with the result that the lever 6 acts as a counterbalance with reference to the lever 5 and the shuttle 4, the levers 5 and 6 being preferably substantially identical with resulting substantially identical weight distribution and being coaxially pivotally mounted, and the cams 38 and 39 having identical lifts and being identically operative on the levers. However, additional weight 42, see Figure 1, may be added to the counterbalancing lever 6 at the shuttle adjacent end thereof to more fully counterbalance the lever 5 and shuttle 4.

A vertically extending strip feed guide is carried with and arranged forwardly of the

frame part 1 in the region of the shuttle 4, and as shown, is of the same construction as that described and claimed in my co-pending application for United States Letters Patent, Serial No. 762,747, filed July 22, 1947, for improvement in Strip Feed Guide, and also embodies structure described and claimed in United States Letters Patent No. 2,374,486, granted April 24, 1945, on my application for improvement in Strip Feed Guide, and will now be described briefly. See Figure 8.

Two series of transversely spaced laterally flexible wire-like longitudinally tensioned guide members 43 and 44 extend longitudinally of the guide and are adjacently spaced facewise of the guide to facewise guide a feed perforated motion picture film strip 45 therebetween. Each series of guide members comprises two widely spaced pairs of adjacently spaced guide members adapted to engage respective of marginal portions of the film strip, and one pair of guide members of each series spans the usual feed perforated portion of the film strip having feed perforations 46 spaced longitudinally of the strip. Two guide rollers 47 are disposed at opposite sides of the guide and extending longitudinally of the guide, edgewise engage the film strip therebetween for edge guiding the same. The strip 45 is thus guided for vertical longitudinal movement, and the guide is so related with a light aperture 48, see Figure 1, through the frame part 1 and disposed upwardly from the shuttle adjacent ends of the levers 5 and 6, that the intermediate picture record portion 49 of the strip passes the light aperture for the projection of light therethrough as an incident of the projection of pictures therefrom.

A laterally flexible wire-like bearing member 51 extends vertically and longitudinally of the feed guide and the film strip 45 guided therein, and is adjacently spaced facewise and rearwardly of the guided strip and disposed substantially opposite the feed perforated portion of the strip having the feed perforations 46. See Figures 1 and 8. The bearing member 51 is carried by the frame part 1 by suitable mounts at its upper and lower ends which longitudinally tension the same, these mounts being fully described in my said co-pending application, Serial No. 762,748, and one of which is shown at 52 in Figure 1.

The lower portion of the bearing member 51 extends in a rearwardly facing groove 53 in the frame plate 1 and this groove communicates with the recess 3. The upper portion of the front surface of the frame plate 1, see Figure 3, is offset rearwardly from the lower portion thereof to form a horizontal portion 54 immediately above the recess 3, and the bearing member 51 extends upwardly from the groove 53 through a relatively large vertical bore 55 through the portion 54, and has its upper portion extending in front of the frame plate, the bearing member 51 extending in coaxial relation with this bore.

The feed shuttle 4 is of elongated tubular form and of relatively small diameter and has its bore 56 engaged on the longitudinally tensioned bearing member 51 between the bearing member mounts for vertical reciprocating strip feed and return movement of the feed shuttle longitudinally of the guided film strip 45 and for oscillatory strip perforation engaging and disengaging movement of the feed shuttle along and about the bearing member 51 which defines an axis extending longitudinally of the guided film strip and adjacently spaced facewise of the guided film

strip and disposed substantially opposite the feed perforated portion of the strip and along which the feed shuttle is reciprocable and about which it is oscillable. See Figures 1, 2, 3 and 7.

The shuttle 4 extends through the relatively large bore 55 through the horizontal frame part portion 54 and upwardly and downwardly therefrom, and the upper portion of the feed shuttle above the bore 55 is provided with a plurality of feed teeth 57 spaced longitudinally thereof in correspondence with the spacing of the feed perforations 46 of the film strip and extending correspondingly radially of the feed shuttle, and these feed teeth are adapted for desirable strip perforation engaging and disengaging movement with oscillatory movement of the shuttle on its axis in an arcuate path extending predominately edgewise of the strip as best shown in Figure 8, the strip feed perforation disengaged and engaged positions of the shuttle teeth 57 being shown respectively in full and dotted lines in this figure. The width of the shuttle teeth 57 longitudinally of the film strip in the guide is less than the corresponding width of the feed perforation 46 of the film strip as is usual.

The lower portion of the feed shuttle below the bore 55 and within the groove 53 is provided with a screwthreaded portion 58 disposed concentrically of the shuttle bore 56 and thus concentrically of the shuttle axis, and the lower end portion of the shuttle is of square external cross section as designated at 59 to provide a square slide bearing extending longitudinally of the shuttle. See particularly Figures 3, 4 and 7.

A suitable packing device 60 is disposed in the bore 55 and surrounds and engages the intermediate portion of the shuttle between the upper feed toothed portion and the lower screwthread and squared portions thereof to prevent lubricant from working upwardly on the shuttle to the upper feed toothed portion thereof where it might otherwise contact the film strip 45 in the feed guide.

A connecting member 61 is provided with a screwthreaded bore 62 through which the feed shuttle 4 passes and with which the threaded shuttle portion 58 is threaded engaged to effect relative movement between the connecting member and feed shuttle longitudinally of the shuttle axis or longitudinally of the reciprocating strip feed and return movement of the shuttle with angular movement of the shuttle on the shuttle axis. See Figures 1, 2 and 3. A bearing stud 63 is formed on the connecting member 61 and extends radially of the axis of the bore 62 and is engaged for pivotal movement in a bore 64 through the shuttle adjacent end of the lever 5 and parallel to the pivotal axis of the lever, so that oscillation of this lever by rotation of the cam 38 effects reciprocating strip feed and return movement of the shuttle along the bearing member 51, the rectilinear reciprocating movement of the shuttle adjacent end of this lever permitting the lever and shuttle to be merely pivotally connected. Angular movement of the connecting member 61 on the axis of the shuttle is prevented by engagement of the stud 63 in the bore 64 and by a vertical surface 65 on the connecting member bearing against the opposing face of the lever 5.

An elongated connecting member 66, see Figures 1, 3, 4 and 5, is mounted within the recess 3 for longitudinal reciprocation transversely of the shuttle axis and corresponding with the planes of movement of the levers 5 and 6 by means of

headed screw studs 67 passing through slots 68 through the member 66 and spaced and extending longitudinally thereof, and screwthreaded into the frame plate 1. A crank member 69 of circular form throughout the major angular extent thereof is engaged for pivotal movement in a horizontal semicircular slot 70 in the frame plate 1 and extending about the groove 53 in coaxial relation with the bearing member 51 and the shuttle 4 so that the crank member is angularly movable on and fixed longitudinally of the shuttle axis. The crank member is provided with a square axial bore 71 in which the lower square portion 59 of the shuttle is angularly fixed and slideable longitudinally of the shuttle axis. Thus, the shuttle is free to reciprocate longitudinally of its axis independently of the crank member 69, while angular oscillation of the crank member effects film perforation engaging and disengaging movement of the shuttle on its axis.

The crank member 69 is provided with a crank pin 72 which is pivotally and slidably engaged in a transverse slot 73 in the connecting member 66 so that longitudinal reciprocation of this connecting member effects oscillation of the crank member to engage and disengage the feed teeth 57 of the shuttle with the feed perforations 46 of the film strip 45. A third radial cam 74 is fixed on the shaft 2 and consequently is fixed with the cams 38 and 39 for rotation therewith, and the connecting member 66 is provided with two parallel vertical extensions 75 between which the cam 74 is engaged so that rotation of this cam effects oscillation of the shuttle 4 on its axis to engage and disengage the feed teeth 57 of the shuttle with the feed perforations 46 of the film strip and by means of the screwthread connection 58—62 effects reciprocation of the shuttle longitudinally of its axis simultaneously with oscillation of the shuttle on its axis to engage and disengage the film strip.

The cams 38 and 74 are so timed that intermittent feed of the film strip in the guide is effected with rotation of these cams, the cam 38 and the cam 74 in cooperation with the screwthread connection 58—62 effecting reciprocatory strip feed and return movement of the shuttle longitudinally of its axis slightly in excess of the feed spacing of the feed perforations 46 of the film strip 45, the cam 38 effecting the major portion of the reciprocatory strip feed and return movement of the shuttle substantially corresponding in extent with the feed spacing of the feed perforations of the film strip, and the cam 74 simultaneously effecting oscillatory strip perforation engaging and disengaging movement of the shuttle on its axis and additional reciprocatory strip feed and return movement of the shuttle longitudinally of its axis in excess of said major portion of this movement, it being observed that the connection between the lever 5 comprises the screwthread connection 58—62 so that the lever 5 and this connection are operative on the shuttle in series.

With rotation of the shaft 2 and cams 38, 39 and 74 in the proper direction, counterclockwise in Figure 1, the cam 74 in cooperation with the screwthread connection 58—62 effects the initial portions of the strip feed and return movements of the shuttle after which the cam 38 effects the major portion of these movements, and the resultant feeding action is as follows:

Referring to Figure 9, the parallelogram 76 indicates the strip feeding cycle of the feed shuttle 4, the arrows associated with the sides of the

parallelogram indicate the directions of movement of the shuttle, the parallelogram sides 77, 78, 79 and 81 indicate respectively the major portion of the strip feed movement, the simultaneous strip disengaging and initial return movement, the major portion of the return movement, and the simultaneous strip engaging and initial feed movement of the feed shuttle 4, and the shuttle and film strip views 82, 83, 84 and 85 respectively adjacent the parallelogram corners indicate the relative positions of a feed tooth 57 of the shuttle and a feed perforation 46 of the film strip 45 at these corners, the shuttle movements 77 and 79 being effected by the cam 38 and the shuttle movements 78 and 81 being effected by the cam 74 in cooperation with the screwthread connection 58—62.

The feed of the film strip 45 is downwardly in Figure 9, and at the termination of the downward strip engaged feed movement 77 of the shuttle, see view 82 of Figure 9, the shuttle tooth 57 is engaged in a strip perforation 46 and against the driven or lower edge 86 of the strip perforation. Following the shuttle movement 77, the shuttle movement 78 takes place and simultaneously disengages the shuttle tooth 57 from the strip perforation 46 and initiates the upward return movement of the shuttle so that the shuttle tooth is lifted from engagement against the perforation edge 86 during the perforation disengaging movement with the result that rubbing of the shuttle tooth on the perforation edge and consequent wear on the shuttle tooth and perforation edges and noise is at least materially reduced. View 83 of Figure 9 shows the relative positions of the shuttle and feed perforation at the completion of the movement 78, the shuttle tooth being disengaged from the film perforation and positioned upwardly from the perforation edge 86.

Following the shuttle movement 78, the shuttle movement 79 takes place during which the major portion of the upward return movement of the shuttle is effected, and at the termination of the movement 79 the shuttle tooth 57 is positioned opposite a succeeding strip perforation 46A in disengaged relation therewith and positioned upwardly from the driven or lower edge 86A of this perforation as shown in view 84 of Figure 9. Following the shuttle movement 79, the shuttle movement 81 takes place and simultaneously engages the shuttle tooth with the strip perforation 46A and initiates the downward feed movement of the shuttle so that the shuttle tooth is lowered downwardly into engagement against the perforation edge 86A during the perforation engaging movement with the result that rubbing of the shuttle tooth on the perforation edge and consequent wear on the shuttle tooth and perforation edge and noise is at least materially reduced. View 85 of Figure 9 shows the relative positions of the shuttle tooth and feed perforation 46A at the completion of the movement 81, the shuttle tooth being engaged with the strip perforation and engaged downwardly against the perforation edge 86A. Following the shuttle movement 81, the shuttle movement 77 takes place during which the major portion of the downward feed movement of the shuttle is effected and the shuttle tooth being engaged with a strip perforation, the film strip is fed downwardly. At the termination of the shuttle movement 77 the perforation 46A is at the former position of the perforation 46 shown in view 82 of Figure 9 with the shuttle tooth engaged in a strip perforation, the move-

ment cycle of the shuttle having been completed and the strip fed the feed spacing of the feed perforations of the strip.

Observing that the cam 38 and the cam 74 in cooperation with the screwthread connection 58-62 cooperate in effecting the reciprocatory film feed and return movement of the feed shuttle 4 and that they are operative in series on the feed shuttle, the cam 38 and its connection with the shuttle constitutes a high velocity means effecting the major portion of the feed and return movement of the feed shuttle at a desirable usual high velocity during the feed movement of which major portion the film strip is fed, and the cam 74 and its connection with the feed shuttle comprising the screwthread connection 58-62 constitutes a low velocity means effecting the initial portions of the feed and return movements of the feed shuttle at a desirable low velocity with a view toward reduction of wear on the shuttle tooth and feed perforations of the film strip and noise, this action being particularly desirable at the initiation of the feed movement of the feed shuttle where the shuttle tooth is engaged against the driven edge of the feed perforation of the film strip preparatory to feeding the film strip. Obviously, the several teeth 57 of the feed shuttle 4 function in the same manner as does the shuttle tooth 57 of Figure 9.

Recalling that the bearing block 1 and the bearing member 22 mounted thereon are adjustable vertically and consequently longitudinally of the reciprocatory strip feed and return movement of the feed shuttle 4, this adjustment provides corresponding adjustment of the pivotal axis established by the bearing member 22 for the levers 5 and 6 and consequent adjustment of the stroking range of the feed shuttle 4 for "framing" the pictures on the film strip 45 with the light aperture 48, and recalling that the stud 14 of which the bearing member 22 forms a part is adjustable with respect to the bearing block 1 correspondingly with the movement planes of the levers 5 and 6 and transversely of the reciprocatory strip feed and return path of the feed shuttle, this adjustment provides corresponding adjustment of the pivotal axis of the levers 5 and 6 and consequent adjustment of the extent of the reciprocatory strip feed and return movement of the feed shuttle and so accommodates for shrinkage or expansion of the strip 45. It will be observed that the hereinbefore described adjustments of the bearing member 22 are correspondingly effective on the levers 5 and 6 so that these adjustments do not alter the counterbalancing action of the lever 6.

While I have thus described my invention, I do not wish to be limited to the precise details described, as changes may be readily made without departing from the spirit of my invention, but having thus described my invention, I claim as new and desire to secure by Letters Patent the following:

1. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a first bearing means establishing a pivotal axis spaced transversely from the reciprocatory path of said feed means and operative on said lever longitudinally of the reciprocatory path of said feed means to corre-

spondingly pivotally confine said lever and to permit relative movement between said lever and pivotal axis radially of said lever and transversely of said reciprocatory path and a second bearing means operative on said lever radially of said lever and transversely of said reciprocatory path to correspondingly confine said lever and to permit pivotal movement of said lever on said pivotal axis and operative in cooperation with said first bearing means to effect substantially rectilinear reciprocation of the feed means connected portion of said lever.

2. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a pivotal first bearing member establishing a pivotal axis spaced transversely from the reciprocatory path of said feed means, a linear second bearing member on said lever and extending radially of said lever and transversely of said reciprocatory path and having bearing engagement with said first bearing member longitudinally of said reciprocatory path to correspondingly pivotally confine said lever and to permit relative movement between said lever and first bearing member radially of said lever and transversely of said reciprocatory path, a third bearing member on said lever, and a fourth bearing member having bearing engagement with said third bearing member radially of said lever and transversely of said reciprocatory path to correspondingly confine said lever and to permit pivotal movement of said lever on said pivotal axis and at least one of said third and fourth bearing members being linear and extending and having a form lineally of said reciprocatory path operative on the other of said third and fourth bearing members to effect substantially rectilinear reciprocation of the feed means connected portion of said lever.

3. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and the pivotal mounting of said lever comprising a pivotal first bearing member establishing a pivotal axis spaced transversely from the reciprocatory path of said feed means, a linear second bearing member on said lever and extending radially of said lever and transversely of said reciprocatory path and having bearing engagement with said first bearing member longitudinally of said reciprocatory path to correspondingly pivotally confine said lever and to permit relative movement between said lever and first bearing member radially of said lever and transversely of said reciprocatory path, a linear third bearing member on said lever in the form of a bearing surface extending and having lineally of said reciprocatory path a convex substantially arcuate form having its axis at the feed means connected portion of said lever, a rectilinear fourth bearing member in the form of a bearing surface extending lineally of said reciprocatory path and having bearing engagement with said third bearing member radially of said lever and transversely of said reciprocatory path, and means operative on said lever radially of said lever and transversely of said reciprocatory

11

path to maintain said third and fourth bearing members in engagement.

4. In an intermittent strip feed mechanism, the combination of toothed strip feed means, a lever mounted for pivotal movement and connected at one end thereof with said feed means for effecting reciprocatory strip feed and return movement of said feed means with oscillation of said lever, a rotatory cam operative on the intermediate portion of said lever for oscillating the same, and the pivotal mounting of said lever comprising a pivotal first bearing member establishing a pivotal axis in the region of the feed means remote end of said lever, a linear second bearing member on said lever at the feed means remote end portion thereof and comprising a slot extending radially of said lever and transversely of the reciprocatory path of said feed means and embracing said pivotal first bearing member for pivotal and radial movement of said lever on said first bearing member, a linear third bearing member on a feed means remote portion of said lever in the form of a bearing surface extending and having lineally of said reciprocatory path a convex substantially arcuate form having its axis at the feed means connected end portion of said lever, a rectilinear fourth bearing member in the form of a bearing surface extending lineally of said reciprocatory path and having bearing engagement with said third bearing member radially of said lever and transversely of said reciprocatory path, and spring means operative on said lever radially of said lever and transversely of said reciprocatory path for maintaining said third and fourth bearing members in engagement.

5. In an intermittent strip feed mechanism, the combination of claim 4 and further characterized in that said third bearing member is disposed at the feed means remote end of said lever and that said first and second bearing members are disposed intermediate the lineal extent of said third and fourth bearing members.

6. In an intermittent strip feed mechanism, the combination of claim 1 and further characterized in that said first bearing means includes a bearing member establishing said pivotal axis and mounted for adjustment corresponding with the movement plane of said lever.

7. In an intermittent strip feed mechanism, the combination of claim 2 and further characterized in that said first bearing member is mounted for adjustment corresponding with the movement plane of said lever and transversely of said reciprocatory path.

8. In an intermittent strip feed mechanism the combination of claim 4 and further characterized in that said first bearing member is mounted for adjustment corresponding with the movement plane of said lever and transversely of said reciprocatory path.

9. In an intermittent strip feed mechanism, the combination of claim 1 and further characterized in that said first bearing means includes a bearing member establishing said pivotal axis and mounted for adjustment corresponding with the movement plane of said lever both transversely and longitudinally of said reciprocatory path.

10. In an intermittent strip feed mechanism, the combination of claim 2 and further characterized in that said first bearing member is mounted for adjustment corresponding with the movement plane of said lever both transversely and longitudinally of said reciprocatory path.

11. In an intermittent strip feed mechanism, the combination of claim 4 and further characterized in that said fourth bearing member is

12

mounted for adjustment corresponding with the movement plane of said lever and longitudinally of said reciprocatory path and that said first bearing member is mounted on said fourth bearing member for adjustment corresponding with the movement plane of said lever and transversely of said reciprocatory path.

12. In an intermittent strip feed mechanism, the combination of claim 4 and further characterized in that said third bearing member is disposed at the feed means remote end of said lever, that said first and second bearing members are disposed intermediate the lineal extent of said third and fourth bearing members, and that said first bearing member is mounted for adjustment in the plane of movement of said lever.

13. In an intermittent strip feed mechanism, the combination of claim 4 and further characterized in that said third and fourth bearing members are disposed at the feed means remote end of said lever, that said first and second bearing members are disposed intermediate the lineal extent of said third and fourth bearing members, that said fourth bearing member is mounted for adjustment corresponding with the movement plane of said lever and longitudinally of said reciprocatory path, and that said first bearing member is mounted on said fourth bearing member for adjustment corresponding with the movement plane of said lever and transversely of said reciprocatory path.

14. In an intermittent strip feed mechanism, the combination of a toothed strip feed shuttle mounted for pivotal strip engaging and disengaging movement and for reciprocatory strip feed and return movement along its pivotal axis, an actuating member mounted for reciprocation longitudinally of said shuttle axis, a connection between said actuating member and shuttle for reciprocating said shuttle along said shuttle axis with reciprocation of said actuating member and comprising a bearing of helical character arranged about said shuttle axis and effecting relative movement between said actuating member and shuttle longitudinally of said shuttle axis with angular movement of said shuttle on said shuttle axis, and means for reciprocating said actuating member and oscillating said shuttle in timed relation to effect intermittent feed of a feed perforated strip.

15. In an intermittent strip feed mechanism, the combination of a toothed strip feed shuttle mounted for pivotal strip engaging and disengaging movement and for reciprocatory strip feed and return movement along its pivotal axis, an actuating member mounted for reciprocation longitudinally of said shuttle axis, a connection between said actuating member and shuttle for reciprocating said shuttle along said shuttle axis with reciprocation of said actuating member and comprising a bearing of helical character arranged about said shuttle axis and effecting relative movement between said actuating member and shuttle longitudinally of said shuttle axis with angular movement of said shuttle on said shuttle axis, and two coaxial rotatable cams angularly fixed with each other and respectively operative on said actuating member and shuttle for reciprocating said actuating member and oscillating said shuttle in timed relation to effect intermittent feed of a feed perforated strip.

16. In an intermittent strip feed mechanism, the combination of a toothed strip feed shuttle mounted for pivotal strip engaging and disengaging movement and for reciprocatory strip feed and return movement along its pivotal axis,

a lever mounted for pivotal movement corresponding with reciprocating movement of said shuttle along said shuttle axis, a connection between said lever and shuttle for reciprocating said shuttle along said shuttle axis with oscillation of said lever and comprising a bearing of helical character arranged about said shuttle axis and effecting relative movement between said lever and shuttle longitudinally of said shuttle axis with angular movement of said shuttle on said shuttle axis, two coaxial rotatable cams angularly fixed with each other and disposed on an axis intermediate the pivotal axis of said lever and said connection and extending transversely of said shuttle axis and one of said cams being operative on said lever to oscillate the same, and a connection between the other of said cams and said shuttle for oscillating said shuttle in timed relation with oscillation of said lever to intermittently feed a feed perforated strip and comprising a crank member angularly movable on and fixed longitudinally of said shuttle axis and angularly fixed with and having slide bearing engagement with said shuttle longitudinally of said shuttle axis.

17. In an intermittent strip feed mechanism, the combination of a longitudinally tensioned wire-like bearing member extending longitudinally of a guided strip, a toothed elongated tubular strip feed shuttle having its bore engaged on said bearing member for reciprocatory strip feed and return movement and oscillatory strip perforation engaging and disengaging movement of said shuttle along and about said bearing member, a lever mounted for pivotal movement corresponding with reciprocating movement of said shuttle along said bearing member, a connection between said lever and shuttle for reciprocating said shuttle along said bearing member and comprising a connecting member pivotally connected with said lever and provided with a screw-threaded bore through which said shuttle passes and a screwthread on said shuttle threadedly engaged with said bore to effect relative movement between said connecting member and shuttle longitudinally of said bearing member with angular movement of said shuttle about said bearing member, two coaxial rotatable cams angularly fixed with each other and disposed on an axis intermediate the pivotal axis of said lever and said connection and extending transversely of said bearing member and one of said cams being operative on said lever to oscillate the same, and a connection between the other of said cams and said shuttle for oscillating said shuttle in timed relation with oscillation of said lever to intermittently feed a feed perforated strip and comprising an axially bored crank member angularly movable and fixed longitudinally of said shuttle axis and in the bore of which said shuttle is angularly fixed and slideable longitudinally of said bearing member.

18. In an intermittent strip feed mechanism, the combination of a toothed strip feed shuttle mounted for pivotal strip engaging and disengaging movement and for reciprocatory strip feed and return movement along its pivotal axis, a lever mounted for pivotal movement corresponding with reciprocating movement of said shuttle along said shuttle axis, a connection between said lever and shuttle for reciprocating said shuttle along said shuttle axis with oscillation of said lever and comprising a connecting member pivotally connected with said lever and a bearing between said connecting member and shuttle and of helical character arranged about said shuttle

10 axis and effecting relative movement between said connecting member and shuttle longitudinally of said shuttle axis with angular movement of said shuttle on said shuttle axis, the pivotal mounting of said lever comprising a first bearing means establishing the lever axis spaced transversely from said shuttle axis and operative on said lever longitudinally of said shuttle axis to correspondingly pivotally confine said lever and to permit relative movement between said lever and lever axis radially of said lever and transversely of said shuttle axis and a second bearing means operative on said lever radially of said lever and transversely of said shuttle axis to correspondingly confine said lever and to permit pivotal movement of said lever on said lever axis and extending and having a form lineally of said shuttle axis operative to effect substantially rectilinear reciprocation of the shuttle connected portion of said lever, and means for oscillating said lever and shuttle in timed relation to effect intermittent feed of a feed perforated strip.

19. In an intermittent strip feed mechanism, the combination of a toothed strip feed shuttle mounted for pivotal strip engaging and disengaging movement and for reciprocatory strip feed and return movement along its pivotal axis, a lever mounted for pivotal movement corresponding with reciprocating movement of said shuttle along said shuttle axis, a connection between said lever and shuttle for reciprocating said shuttle along said shuttle axis with oscillation of said lever and comprising a connecting member pivotally connected with said lever and a bearing between said connecting member and shuttle and of helical character arranged about said shuttle axis and effecting relative movement between said connecting member and shuttle longitudinally of said shuttle axis with angular movement of said shuttle on said shuttle axis, the pivotal mounting of said lever comprising a first bearing means establishing the lever axis spaced transversely from said shuttle axis and operative on said lever longitudinally of said shuttle axis to correspondingly pivotally confine said lever and to permit relative movement between said lever and lever axis radially of said lever and transversely of said shuttle axis and a second bearing means operative on said lever radially of said lever and transversely of said shuttle axis to correspondingly confine said lever and to permit pivotal movement of said lever on said lever axis and extending and having a form lineally of said shuttle axis operative to effect substantially rectilinear reciprocation of the shuttle connected portion of said lever, two coaxial rotatable cams angularly fixed with each other and disposed on an axis intermediate said lever axis and said connection and extending transversely of said shuttle axis and one of said cams being operative on said lever to oscillate the same, and a connection between the other of said cams and said shuttle for oscillating said shuttle in timed relation with oscillation of said lever to intermittently feed a feed perforated strip and comprising a member having slide bearing engagement with said shuttle longitudinally of said shuttle axis.

20. In an intermittent strip feed mechanism, the combination of a toothed film feed means, a pair of levers substantially coaxially pivotally mounted for independent pivotal movement and extending correspondingly from their pivotal axis in overlying relation and a first of said levers being connected with said feed means for effect-

ing reciprocatory strip feed and return movement of said feed means with oscillation of this lever, means for oscillating said levers in timed opposite movement phase relation whereby the second of said levers acts as a counterbalance, and the pivotal mounting of said levers comprising a first bearing means establishing a pivotal axis spaced transversely from the reciprocatory path of said feed means and operative on said levers longitudinally of said reciprocatory path to correspondingly pivotally confine said levers and to permit relative movement between said levers and said pivotal axis radially of said levers and transversely of said reciprocatory path and including adjustable means operative to adjust said pivotal axis radially of said levers and transversely of said reciprocatory path and a second bearing means operative on said levers radially of said levers and transversely of said reciprocatory path to correspondingly confine said levers and to permit pivotal movement of said levers on said pivotal axis and operative in cooperation with said first bearing means to effect substantially rectilinear reciprocation of the feed means connected portion of said first lever and the corresponding portion of said second lever.

21. In an intermittent strip feed mechanism, the combination of claim 20 and further characterized in that said first bearing means includes a second adjustable means operative to adjust said pivotal axis longitudinally of said reciprocatory path.

22. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and bearing means

operative on said lever remote from the pivotal axis thereof to confine the same normal to its plane of movement and comprising at least one longitudinally tensioned wire-like bearing member extending correspondingly with movement of said lever and having bearing engagement therewith.

23. In an intermittent strip feed mechanism, the combination of toothed strip feed means, a lever mounted for pivotal movement and connected with said feed means for effecting reciprocatory strip feed and return movement of said feed means with oscillation of said lever, means for oscillating said lever, and bearing means operative on said lever remote from the pivotal axis thereof to confine the same normal to its plane of movement and comprising two parallel longitudinally tensioned wire-like bearing members extending correspondingly with movement of said lever and between which said lever is disposed and having bearing engagement therewith and mounting means common to said bearing members and operative to position and tension the same.
